UNITED STATES PATENT OFFICE.

FRANCIS H. RICHARDS, OF HARTFORD, CONNECTICUT, ASSIGNOR TO THE PRATT & WHITNEY COMPANY, OF SAME PLACE.

REGISTER FOR GRAIN-WEIGHERS.

SPECIFICATION forming part of Letters Patent No. 447,719, dated March 3, 1891.

Application filed September 20, 1890. Serial No. 365,631. (No model.)

To all whom it may concern:

Be it known that I, FRANCIS H. RICHARDS, a citizen of the United States, residing at Hartford, in the county of Hartford and State of Connecticut, have invented certain new and useful Improvements in Registers for Grain-Weighers, of which the following is a specification.

This invention relates to register apparatus for registering the movements of machine elements, and more especially the scale-beam movements of grain-weighing machines.

In the drawings accompanying and forming a part of this specification, Figure 1 is an end elevation of registering apparatus shown in connection with portions of a grain-weigher and connected for registering the vertical movements of the scale-beam. Fig. 2 is a plan view of the registering apparatus and accessory parts shown in Fig. 1. Fig. 3 is a front elevation of the same. Fig. 4 is a plan view drawn on an enlarged scale and having the upper portions of the register-case and ratchet-case broken away to better show the inclosed details. Fig. 5 is a front view with the front plate removed for showing the details in the register-case. Fig. 6 is a front view of the ratchet-case and lever with the ratchet-case cover removed to show the actuating-paws. Fig. 7 is a sectional view in the line *a a*, Fig. 6, showing the preferred construction of the lever at that point. Fig. 8 is a vertical section in line *y y*, Fig. 4, as seen from the right hand in said figure. Fig. 9 is a similar section in line *x x*, Fig. 4.

Similar characters designate like parts in all the figures.

In the drawings, Figures 1, 2, and 3, my improved registering apparatus is shown applied to the grain-weigher of the type described in the Letters Patent No. 442,724, granted to C. H. Cooley and F. H. Richards, December 16, 1890; but it is equally applicable to grain-weighers of other classes and also to other kinds of machines in which it is required to register reciprocating movements of some part of the machine. As shown herein, the supply-chute *H* is carried by the top plate 5, which is supported on the framework of the grain-weigher. Said supply-

chute thus constitutes a part of the framework for carrying the operative parts of the machine. It is furnished with knife-edges, as 24, for supporting the scale-beam *B*. For actuating the register from the scale-beam I provide said beam with a register-actuating arm—as, for instance, the arm 405, which is fixed by screws 406 or otherwise to the bucket-carrying arm 19 or to the shaft 50 of the scale-beam. The forward end of said arm 405 suitably engages the ratchet-arm 423 of the register, and thus on the rising of the scale-beam imparts to said ratchet-arm a rotary reciprocating movement, as herein more fully described in connection with the diagrammatic view, Fig. 6.

The frame-work of the register consists of the register-case 407, which is shown attached to the front wall of the chute *H* by means of ears 408, formed on said case and secured to said front wall by screws 409, and the front plate 410 removably secured to the front of and closing the register-case. Said front plate may be held in place by screws, as indicated in Fig. 3. For convenience in assembling and disassembling the mechanism, the front plate is formed in two parts divided at the line 411, the portion at the right hand of said line being provided with a bearing 412 for the ratchet-shaft 413, whose rear end is journaled, as indicated in Fig. 8 in a bearing formed in the back plate 414 of the register-case. Fixed on said shaft between its said bearings and within the register-case are two wheels 415 and 416, of which the first wheel 415 is a spur-wheel meshing with the first register-wheel of the series, the second wheel 416, fixed on said shaft, being a detent-wheel engaged by the detent-pawl 417, that is pivoted at 418 on a pin fixed in the frame-work. This detent apparatus will be understood by comparison of Figs. 4, 5, and 8 of the drawings. For holding the detent-pawl firmly in engagement with said detent-wheel a spring 419 is provided, one end of which is set in engagement with the pawl, as indicated in Fig. 5, the other end reacting against an abutment provided therefor—as, for instance, the pin or stud 420, cut away, as indicated in Figs. 4 and 5, to form a steady-pin standing within end coils of the

aforesaid spring 419. Said stud 420 and also the detent-pawl pivot 418 are both preferably fixed in said front plate 410, whereby on removal of the front plate all said details are removed together, thus facilitating the assembling of the mechanism. The preferred means for fixing in place the wheels 415 and 416 on the ratchet-shaft is shown in Fig. 8, where the hub of each wheel is bored to receive screw-pins, as 421, whose straight and unthreaded portion 422 passes through the shaft and one side of said hub, the enlarged end of said pin being threaded to screw into the other side of said hub.

15 The ratchet-arm 423 has formed thereon a ratchet-case 424, whose back plate 425, Fig. 8, has a bearing 439, fitting on the ratchet-shaft 413 immediately forward of the shaft bearing 412, as best shown in Figs. 4 and 8. The front of the ratchet-case is tightly closed by the ratchet-case cover 426, in whose middle part there is a bearing 427, fitting the outer end of said ratchet-shaft. Said outer bearing is formed on the inner side of the outwardly-projecting part 428 of said ratchet-case cover, as indicated in Fig. 8, where the ratchet-wheel 429 is shown fixed on said shaft by means of its hub 430, and one of the aforesaid pins 421 passing through said shaft and hub, as in the case of the wheels 415 and 416, above described. It will be observed in Fig. 8 that the pin 421, holding in place said ratchet-wheel, is outside of the front line of the ratchet-case, so that when the ratchet-case cover is removed said pin is readily accessible by means of a screw-driver in alignment therewith, whereby the pin and ratchet-wheel are readily removable. To remove the ratchet-arm from the ratchet-shaft, the ratchet-case cover 426 is first taken off, the pin 421 then unscrewed and taken out, and the ratchet-wheel 429 next taken from its shaft, when said arm will be free to be slid forward off from said shaft 413. As indicated in Figs. 3 and 6, the ratchet-case is set eccentric to the ratchet-shaft 413, so as to form a sufficient space at one side of the ratchet-wheel for receiving the duplicate pawls 431 and 432, which are pivotally supported on pins 433 and 434, fixed in the back plate of said ratchet-case. For preventing undue movement of the pawls away from the ratchet-wheel, stops 435 and 436 are provided for said pawls, respectively. The pawls 431 and 432 are similarly located, as indicated in Fig. 6, relatively to the periphery of the ratchet-wheel 429, and are supposed to be of substantially similar construction and size, so that said pawls may change places and also change positions without affecting their operation. For this purpose the front or working end 437 of the pawl has two faces, only one of which bears on the ratchet-wheel tooth, as shown in Fig. 6. When the pawls are taken off, as required in cleaning the mechanism, either pawl may be replaced in either position and either side first. This interchangeability is found to be extremely

desirable to prevent accidental misplacement by inexperienced mechanics, to whom this class of machinery is necessarily intrusted. Two similar pawls are here provided, as here described, because a certainty of operation is thereby secured, it being demonstrated by experience as well as indicated by theory that the chances of failure of operation are very greatly reduced by duplication of the pawls. For instance, if in ordinary practice one of the pawls will fail to perform its work once in each one thousand movements the probability that both would fail at the same time would be only one in one thousand times one thousand, or one in a million. As a means for preventing as much as possible the sticking of the pawls on their pivots, they are in the first place freely fitted, and, second, the middle portion of the pawl is cut out, as at 438, Fig. 4, thus leaving two narrow bearings in contact with the pin, said bearings being each much larger in diameter than in length. The ratchet mechanism carried by the ratchet-arm is thus inclosed in a closely-covered case, whereby access of dust is effectually prevented. The only free access to the interior of said ratchet-case (and this the freedom of a working joint only) is through the working-space between the shaft 413 and the bearing 439 of the back plate of the ratchet-case. This space, however, must be reached through the joint at 440, Figs. 4 and 8, so that in practice the ratchet-case may be considered as perfectly dust-proof. The importance and practical utility of this organization of the ratchet mechanism will be at once appreciated by those familiar with milling machinery and the well-known penetrating power of mill-dust.

The ratchet-arm is operated by the aforesaid arm 405, which engages in the slot or mortise 441 of the ratchet-arm, as indicated in the general views, Figs. 1, 2, and 3. As indicated in Fig. 3, the upper surface of said arm 405 is rounded where it bears against the under side of the ratchet-arm 423, the under side of said arm 405 being there beveled to prevent clogging by grain accidentally thrown thereon. For the same purpose, also, the guard-loop 442 of the ratchet-arm is beveled on the upper side, as indicated in the sectional view, Fig. 7. The normal movement of the ratchet-arm during the operation of the mechanism corresponds, of course, to the angle of the ratchet-teeth, being somewhat more than said angle, as indicated, for instance, by the dotted radial lines 443 and 444, Fig. 6.

As will be seen by comparison of Figs. 4 and 5, the first dial D' of the set of register-dials D is located at one side of the ratchet-shaft 413 a sufficient distance, so that the proper character on said first dial may be seen through the opening 460 in the front cover of the register-case. This arrangement permits said dial to be readily seen notwithstanding the location of the ratchet-case 424,

which stands in front of one end of the register-case 407. The openings 460 are closed by a glass plate 461, which is usually cemented to the inner side of the front plate 410, as indicated by the darkened layer 462 in Fig. 4, as will be readily understood without further description. Referring to and comparing Figs. 3 and 5, it will be seen that in Fig. 3 the characters "0," "1," and "2" of the dials D³, D², and D', respectively, are shown through said front-plate openings, so that in this instance the register reads "12."

For carrying the regular disks or dials D', D², and D³, respectively, the back plate 414 has fixed thereon a series of suitable studs at 445^a, 445^b, and 445^c.

The spur-wheel 415, which is fixed as aforesaid on the ratchet-shaft 413, meshes with the spur-wheel or pinion 446, that is supported to turn freely on the stud 445^a. Said pinion is provided with a driving-wheel 447, which is of a well-known kind and form, and has one tooth or projection 448 formed thereon for engaging the notches 449, (ten in number,) that are formed in the driven wheel 450, carried on stud 445^b. Said stud 445^b also carries a driving-wheel 451, (similar to wheel 447,) having one tooth 452 formed thereon to engage the notches 453, that are formed in the driven wheel 454, which wheel is similar to the wheel 450 and is carried on the stud 445^c.

In operating the register the first dial D' is moved forward intermittently nine times before the driving-wheel 447 engages the wheel 450 of the second dial. At the next movement of the dial D' the second dial is turned forward uniformly with the first dial. This cycle of operations is repeated nine times before the driving-wheel 451 of the second dial 40 engages the driven wheel 454 of the third dial D³ to turn the same forward one division. These features of operation, however, are well understood in the prior art, and will be obvious from the drawings without further explanation.

Fig. 9 is a vertical section in line x x of Fig. 4, and illustrates one method of assembling the parts carried on the dial-supporting studs. As the parts are similarly assembled on all three of the studs 445^a, 445^b, and 445^c, a description of one set of said parts will be sufficient for the clear understanding of all three sets, notwithstanding said sets are not exactly duplicates. Referring to Fig. 9, a sleeve 455 is shown bored to loosely fit the stud 445^b, which stud is reduced in diameter for a portion of its length for the purpose of reducing the friction thereon. On said sleeve 455 are fitted the figured dial D², the toothed driving-wheel 451, and the notched driven wheel 450. Suitable distance-rings, as 456, are provided to properly separate the said wheels. In practice, when the several parts are assembled on said sleeve and correctly adjusted circumferentially thereof they are then soldered or pinned together, and thus held in their proper relative positions as if formed integral, and

it should be well understood that the said parts are not necessarily made separate, but are so constructed only for the purpose of facilitating construction. Said sleeve and the several parts shown carried thereon may be formed integral, if this construction should in any case be preferred.

As shown in Figs. 3 and 4, openings are formed in the front plate 410 of the case, so that one numeral on each of the figured disks D D', &c., may be seen one at a time. Usually in practice the uppermost central numeral is the one seen. An indicator-pin 459, whose inner projecting end is pointed, as shown in Figs. 4 and 6, is fixed in the ratchet-arm 423, and two notches or suitable reference-lines, as 457 and 458, are formed in the right-hand edge of the front plate 410 of the register-case at points corresponding to the extreme upper and lower positions of the said ratchet-arm. The said pin or pointer and the said notches are provided so that at any time the positions of the parts contained and hidden in the ratchet-case may be judged by the position of the said pointer relative to the said notches.

Having thus described my invention, I claim—

1. In register mechanism, the combination, with the dial-actuating shaft projecting from the register-case, of a ratchet-case, substantially as described, journaled on said shaft and connected for rotary reciprocating movement, the ratchet-wheel fixed on the shaft within said case, two pawl-carrying pins fixed in said case at equal distances from said ratchet-wheel, and two interchangeable gravity-pawls, substantially as described, carried on said pins, whereby a certainty of operation and the correct assembling of the parts are attained.

2. In register mechanism, the combination, with the dial-actuating shaft projecting from the register-case, of a ratchet-case, substantially as described, journaled on said shaft and connected for rotary reciprocating movement, the ratchet-wheel fixed on the shaft within said case, the pawl-carrying pin fixed in the case, the gravity-pawl carried freely on said pin and engaging the ratchet-wheel, and the stop limiting the outward movement of the pawl to slightly clear the ratchet-wheel tooth on the return movement of the ratchet-case.

3. In register mechanism, the combination, with the dial-actuating shaft projecting outside of the register-case, of the register-case journaled on said shaft and having a cover also journaled on said shaft, said cover having a projecting hub-case 428, the ratchet-wheel 429 on said shaft within said case and having its hub projecting beyond the front of the ratchet-case within said hub-case, and a pin, substantially as described, passing through the ratchet-wheel hub and engaging said shaft, said pin being located beyond the front line of the ratchet-case when the ratch-

et-case cover is removed, whereby the pin is accessible for removal, substantially as set forth.

4. In register mechanism, the combination, 5 with a register-case and a ratchet-case, of a dial-actuating shaft extending into both said cases, a portion of the shaft intermediate thereto being covered by a projecting hub, as 412, whereby access of dust to the interior 10 of the said cases through the working-joint 440 is prevented, substantially as set forth.

5. In register mechanism, the combination, 15 with a register-case, substantially as described, of the ratchet-shaft having fixed

thereon a detent-wheel within the register-case, a detent engaging said wheel, a ratchet-case carried on the projecting end of said shaft, a ratchet-wheel fixed on said shaft within the ratchet-case, a pawl carried by the ratchet-case and engaging with said ratchet-wheel, and an indicator, substantially as described, for indicating the position of the enclosed parts by the position of the ratchet-case relatively to the register-case. 20
